UNITED STATES PATENT OFFICE.

DAVID N. OSYOR, OF COLUMBUS, OHIO, ASSIGNOR TO JOSEPH A. JEFFREY, OF COLUMBUS, OHIO.

MINING-MACHINE.

No. 889,148.

Specification of Letters Patent.

Patented May 26, 1908.

Application filed January 8, 1894. Serial No. 496,167.

To all whom it may concern:

Be it known that I, DAVID N. OSYOR, a citizen of the United States, residing at Columbus, in the county of Franklin and State of Ohio, have invented certain new and useful Improvements in Mining-Machines, of which the following is a specification, reference being had therein to the accompanying drawings.

10 Figure 1 is a side view of a mechanism embodying my improvements. Fig. 2 is a sectional view on the line $x-x$, Fig. 1, showing the supporting frame in face view, the parts behind said frame and the driving 15 chain being omitted. Fig. 3 is a side view of the cutting apparatus on a larger scale. Fig. 4 is a sectional view taken horizontally through the supporting frame and the trunnioned ring, and vertically through the interior ring or disk, the latter being adapted 20 to be turned at times at right angles to the position shown in Fig. 2, at which times Fig. 4 is throughout a horizontal section on line $y-y$, Fig. 2. Fig. 5 is a plan view with part 25 in section, of the power and feeding apparatus. Fig. 6 shows the rocking carrier, or ring, detached. Fig. 7 is a horizontal longitudinal sectional view through the cutter-head and its support, the parts being in the 30 relative positions shown in Fig. 3. Fig. 8 is a similar view with the cutter-head turned through a quarter of a revolution. Fig. 9 is a perspective view of one of the cutter-head supports. Fig. 10 is a perspective 35 view of one of the non-vibrating cutters. Fig. 11 is a perspective view of the cutting and driving wheel. Fig. 12 shows two sectional views of one of the cutter-head disks taken on lines at right angles to each other. 40 Fig. 13 is a sectional view through one of the cutter-head disks with one of the non-vibrating cutters in place. Fig. 14 is a sectional view through the same disk with the vibrating cutter in place thereon. Fig. 15 45 is a perspective view showing the inner face of one of the cutter-head disks. Fig. 16 is a perspective view showing the outer face of one of said disks.

In the drawings a frame-work is shown, 50 such as I at present prefer to employ, but it will be understood that a number of the features of invention are not dependent upon

the particular details shown. The one illustrated is formed with the uprights a , a' , top and bottom cross bars, and the top and bottom fastening pins as at B , B' , one or both of the latter being provided with a hand nut, and pointed sleeve, as at B' . This frame, as a whole, is indicated by A . The upright a' is provided with eyes or bearings a^2 , a^3 , 55 to hold an adjusting rod to be described.

A vertically adjustable frame or support for the cutting apparatus and other parts is indicated by C , C' , these being tubular or angular pieces fitted to, and sliding upon the 60 uprights a , a' . Each has a trunnion socket at c , and the part C' has an eye at c' , which as a whole is threaded, or is adapted to have secured to it a nut-like part.

D indicates a threaded rod mounted in the 65 aforesaid bearings a^2 and a^3 , and passing through and engaging with the threaded part at c' . It has a crank or hand wheel at d , by which it can be readily turned at any time so that the support C , C' , can be adjusted up or down longitudinally of the 70 frame A , as required.

The part which immediately carries the cutters is indicated by E . As shown in Figs. 2, 4, and 5, it is made of angle iron, having 75 the flanges e , e' , so as to be light, and yet sufficiently strong. It is connected to the column or upright support A by means of a trunnioned ring F , and a disk or pivot plate G . The trunnioned part F has trunnions 80 f , f' , fitted in the aforesaid sockets c , c' . This ring supports a rotary disk or pivot plate G , preferably by being grooved or formed with flanges f^3 at the edges, so that the part 85 G can be fitted therein. The connection between them can be left loose so that more or less rotation of the pivot plate G about its longitudinal axis relative to the ring F can be effected at any time; or it can be made rigid with the ring F by drawing up tightly the 90 two ends of the ring F by the screw f^2 , which passes through the lugs f' thereon.

The pivot plate G has a central aperture, through which the bar E passes; and also apertures for the free passage of a chain used 95 for a purpose to be described. In order to give a prolonged support for the bar E , and for the chains, tubular projections are formed on or secured to the part G , as shown in Fig.

4, at H, H, said projections being flared at the ends h.

The cutter carrier E can be fed forward or drawn back longitudinally by means of a threaded feed rod I, and the nut I' mounted on plate G. This rod is mounted in bearings i, i', and carries a bevel wheel I² adapted to be rotated by hand or by power.

The cutting apparatus, proper, which is shown, is indicated as an entirety by J. It consists of a cutting and driving wheel L mounted between heads or disks M, M', which are supported in bearing bars K, K, bolted to the front end of the carrier E. Each of these bearing bars is formed with an attachment arm k, and a forwardly projecting plate-like ring k', with an aperture k². The forward part k' of each bearing bar is tapered or gradually reduced in thickness, as shown in Figs. 7, 8, and 9.

The wheel L is formed with sprocket teeth, some narrower as at l, and others broader as at l', the latter being provided with detachable cutters l². Inside of the peripheral parts of the wheel there is a reduced web l³, and at the center a hub l⁴, which at its opposite ends is beveled or tapered inward, as at l⁵, the hub being constructed with a relatively large centrally arranged oil reservoir l⁶ (see Figs. 7, 8, and 11.)

The tapered or beveled sockets l⁵ in the ends of the hub are preferably square in cross section for a purpose hereinafter to be described. To this hub, a bushing of brass, or some other suitable bearing metal is fitted, preferably formed of two tubes or ferrules, L', L', each arranged to receive one of the ends of the hub. These bushings are preferably tapered, so that when fitted into the bearing bars K their upper and lower surfaces will be flush with the upper and lower surfaces of the said bars.

The two heads or disks M, M', of the cutting apparatus, which are substantially similar in form, are arranged on opposite sides of the cutter wheel L, and each has a centrally arranged, inwardly extending, tapering boss m', square in cross section and having a cylindrical passageway extending centrally therethrough.

In the outer faces of each of the heads or disks M, M', are formed grooves m², m³, intersecting each other at the center of the disk at right angles. The groove m² extends across the face of the disk and has a curved bottom wall m⁴ lower than the bottom wall of the groove m³. The side walls of the groove m³ are preferably oppositely inclined to its bottom wall, as shown. In these grooves in the disk M are fitted cutters N, O, respectively; and in the corresponding grooves in the disk M', are fitted similar cutters N', O'.

The cutters N, N', are so shaped on their inner sides as to permit them to rock across

planes which are transverse to the axis of the disks which carry them. Each is recessed at n, on each side of the center, and is formed with an enlarged eye or ring n' at the center. The recesses n extend to a radial distance, a little greater than the radius of the periphery of the bushing L' from the axis of the disks, so that the thicker part of the cutter, in fact, the cutting edge proper n³ can move inward past the outer edge of the bottom wall m⁴ of the groove m² and lie closely adjacent to the outer tapering surface of the adjoining bearing support K. The bottom wall of the recess n rests upon the bottom wall of the groove m² and is adapted to rock thereon.

The cutters O, O', are, as said above, fitted in the grooves m³, and adapted to be secured rigidly to the heads or disks M, M'. Each is formed with a tubular boss o, which passes loosely through the eye or ring n' in the adjacent cutter N, N', and is adapted to be fitted snugly in a recess m⁵ in the boss m' of the disk which carries it. The side edges of the cutters O, O', are preferably inclined to the top and bottom walls of the cutters and are arranged to engage the inclined side walls of the grooves m³.

The manner of arranging the parts above described, and also the manner in which they operate, will be readily understood from the description in connection with the drawings. The wheel L, the cutter heads or disks M, M', and the cutters carried thereby after being placed properly in the bearing bars K, are all clamped together by a bolt or screw P, having one end countersunk in the cutter O and the other end screwed into the cutter O'.

The cutters l² in the wheel L act to remove the material from the front of the cutting and driving wheel. The cutters O, O', act similarly to remove all that lies directly in front of the cutter heads M, M'. That which lies in front of the bearing bars K, K, is reduced and removed by the vibrating cutters N, N', since when the cutting part proper n³ at either end of each cutter is traversing the forward portion of its circle, it can move inward and lie in that plane transverse to the axis of rotation in which the outer portion of the adjacent bar K lies, the cutters N, N', at such times lying in a plane inclined to the plane of the main or driving cutter wheel L of the apparatus. The forward end of each of the cutters N, N' is at such times, compelled to thus swing or move into the plane of the adjacent bearing bar K, because of the fact that the other, or at that time rear end, of each of said cutters is moving over the rear surface of the adjacent inclined plate k', which being at a greater distance from the longitudinal axis of the machine than is the front surface of the plate, acts as a cam to rock the cutter in its carrying disk, swinging its front cutting edge n³ inward and

its rear cutting edge outward. In this way a perfectly clear path is provided for the cutting apparatus proper, and for its carrier.

The cutter wheel L is rotated by the chain 5 Q, which extends back to a driving wheel Q', supported on the part I³, and bar E, it being upon a shaft i⁴. This shaft has a gear wheel Q² with which a pinion r engages, the latter being driven by the armature of an electric 10 motor indicated as a whole by R, and supported upon the cutter carrier. One strand of the chain lies above, or at one side of the carrier E, and the other lies below it, or on the opposite side. They pass through the 15 tubular guides H, H, in the adjustable support, and are therein held properly in position in driving relation to the wheels L and Q'. Q³ is a gear wheel mounted on the shaft i⁴ and adapted to be actuated by the motor 20 and to engage with and rotate the gear I². This wheel Q³ is preferably rigid with the gear Q² which is slidably fitted on the shaft by a spline, so as to rotate therewith, and yet be capable of longitudinal movement thereon 25 so as to permit gear Q³ to be moved into and out of engagement with the pinion I².

If it is desired to feed by hand, a wheel S² is provided which can be put into engagement with the wheel I², it being supported 30 on a shaft s mounted in a suitable bearing wherein it can be moved longitudinally to cause the wheel S² to engage with, or be disengaged from the gear I². S' is a hand wheel for operating the shaft s.

The machine which I have shown and above described, can be used either for "shearing", that is to say forming a vertical cut, or for forming a horizontal one, at the floor line, that is an "undercut", or it can 40 be used to form an inclined cut, or to work an excavation around masses of foreign materials, such as "sulfur balls." In Fig. it is arranged for shearing or forming a vertical cut. If it is assumed that an electric current is entering the motor R, and causing it to actuate the driving parts, it will be seen that the cutting apparatus at J will be rotated by the chain Q, and that the cutter carrier E and the cutter will be advanced by the threaded rod I and nut I'. While the cutters are rotating, 45 they can be rocked or vibrated up and down, the trunnioning at f, f, permitting such movement. At the same time they are capable of being rocked or vibrated in horizontal 50 planes about the axis of the fastening pins or bars B, B. Therefore a vertical cut can be formed in a plane at any desired angle to the face of the coal. In order to cut a horizontal kerf it is only necessary to loosen the plate G by the screw f². When the parts of the ring F have been separated slightly, the plate G and parts connected therewith can be rocked 55 about the axis of said plate, which extends longitudinally of the apparatus in the direction of the length of the shaft I to bring the

cutters to the desired plane. After such adjustment, it may be clamped tightly in position, or it may be left loose, so that the cutters can be varied somewhat from the horizontal plane, as may be necessary in passing 70 around an obstruction or in following the curvatures of a slate vein, or layer of sulfur. In short, it will be seen that under this arrangement, and adjustment of the parts, the cutters and the cutter carrier are capable of 75 universal adjustment.

It will be noted that the power is applied directly to the cutting and driving wheel L, and that such wheel is so connected with the cutter heads or disks M, M', as to rotate them, 80 and the cutters N, N' and O, O'; the cutters N, N', operating in planes inclined to the planes of the main wheel L, as well as to the planes of the cutters O, O', and being adapted to remove the coal between the main 85 wheel L and the cutters O, O'.

The oil reservoir l⁶ is capable of holding a comparatively large quantity of oil which can pass through the ducts o' to the outside of the brass bushings which fit in the bearing bars K, and as the bushings are comparatively large, a large wearing surface is provided and durability is insured.

What I claim is:

1. In a coal or rock cutting mechanism, 95 the combination of a frame adapted to be made stationary, a cutting apparatus adapted to swing vertically and horizontally and to cut continuously while swinging, a longitudinally movable frame supplemental to the 100 cutting apparatus and supported on the stationary frame and adapted to be rotated around an axis which extends through the cutting apparatus and on lines parallel to the lines of longitudinal movement of the movable frame, substantially as set forth.

2. In a mechanism for cutting coal or rock, the combination of a frame adapted to be made stationary, a cutting apparatus adapted to swing vertically and horizontally 110 relatively to the stationary frame and to cut on lines parallel to the path of advance of the cutting apparatus, a longitudinally movable frame supplemental to the cutting apparatus and supporting it, said longitudinally movable frame being rotatable around an axis parallel to the path of longitudinal movement of the longitudinally movable frame and intersecting the axis around which the cutting apparatus swings horizontally, substantially as set forth.

3. In a mechanism for cutting coal or rock, the combination of a frame adapted to be made stationary against reactionary movement and adapted to be rotated horizontally around a vertical axis, a longitudinally advancing cutting apparatus adapted to cut on lines crossing the lines of advance and also on lines parallel thereto, and a frame supplemental to the cutting apparatus for 125

130

supporting it, said frame being adjustable longitudinally relatively to the stationary frame and adjustable horizontally therewith and adapted to be rotated around an axis 5 intersecting the vertical axis of the stationary frame, substantially as set forth.

4. The combination with the main frame, the cutting apparatus, the carrier for said apparatus, the motor mounted on said carrier, the ring F having trunnions fitted in bearings on the main frame, the plate G fitted in said ring and connected with the cutter, the chain for transmitting power from the motor to the cutting apparatus and 10 the guides H for said chain mounted in the plate G, substantially as set forth.

5. In a cutting apparatus for a mining machine, the combination of the wheel having a series of peripheral cutters, and the disk or 15 plate connected to and rotating with said wheel and having a cutter adapted to move toward and from the planes of rotation of the peripheral cutters on said wheel and means for automatically vibrating the said cutter 20 on the disk, substantially as set forth.

6. In a mining machine, the combination of the wheel having a series of peripheral cutters, the support or bearing for said wheel, and the disk or plate connected with the 25 wheel and lying on the opposite side of the support or bearing therefrom and having an auxiliary cutter adapted to move toward and from the wheel across the planes of the bearing, to cut a path therefor, and means intermittently engaging with said auxiliary cutter 30 to move it as described substantially as set forth.

7. The combination of the carrier bar E, means for adjustably supporting said carrier 40 bar, the driving chain supported by said bar, power devices for actuating the chain, the chain wheel at the front end of the bar, the peripheral cutters in said wheel, the bearing at the side of the wheel, the rotary auxiliary 45 cutter support outside of the bearing, and the auxiliary cutter on said support, vibratable toward and from the chain wheel, and means for intermittently moving the auxiliary cutter toward and from said wheel, 50 substantially as set forth.

8. The combination of the main frame, the cutter carrier, the cutter wheel at the front end of said carrier rotating on a fixed axis, a bearing for said wheel, and an auxiliary cutter outside of said bearing rotating 55 on a fixed axis and vibratable relative to its axis toward and from the longitudinal lines of the said cutter carrier, substantially as set forth.

60 9. The combination of the main frame, the cutter carrier, means for moving said carrier longitudinally, a cutter wheel having peripheral cutters on the central longitudinal lines of the carrier, power devices for rotating said wheel arranged longitudinally along

said carrier, a bearing on the carrier for said wheel, an auxiliary cutter support outside of the bearing rigidly connected to the wheel, an auxiliary cutter on said support rotating therewith, and vibrating relatively thereto and relatively to its planes of rotation, substantially as set forth. 70

10. The combination of the main frame, the longitudinally advancing cutter carrier, the cutter wheel at the front end thereof, 75 means extending longitudinally of the carrier for rotating said wheel, the bearing on the carrier for said wheel, the cutter support outside of said bearing, one or more auxiliary cutters on said cutter support, rotating in fixed relation therewith, and one or more auxiliary cutters on said support rotating therewith but also vibrating relatively to the plane of rotation thereof, substantially as set forth. 85

11. The combination of the cutter wheel, the shaft-like support for the wheel, the longitudinally movable bar or frame carrying said shaft-like support, and having its outer face tapered in front of the axis of 90 the wheel, the auxiliary cutter rotating with and vibrating in relation to the wheel, and means for moving the auxiliary cutter toward said tapered face, substantially as set forth. 95

12. The combination of the cutter wheel, a shaft-like support therefor, the bar or frame carrying the shaft-like support, and having the wheel on one side thereof, the rotary plate or support M on the opposite 100 side of the bar, an auxiliary cutter bar loosely mounted on said plate M and extending across its axis and having a cutter at its end, and means engaging with the opposite end of the cutter bar for vibrating the 105 cutter toward and from the wheel, substantially as described.

13. In a cutting apparatus for mining machines, the combination with the wheel having a series of peripheral cutters, of the 110 support or bearing for said wheel, a disk or plate arranged on the opposite side of the bearing from and adapted to be actuated by the cutting wheel, a stationary cutter carried by said disk and adapted to cut a path 115 therefor parallel to that cut by the cutters on the wheel, and another cutter carried by said disk and adapted to move toward and from the cutting wheel and cut a path for the bearing or support therefor, substantially as set forth. 120

14. In a cutting apparatus for mining machines, the combination of the wheel having the series of peripheral cutters, and the projecting hubs, the bearings or supports 125 having openings to receive the hubs on said wheel, and the disks or plates secured to said hubs, on opposite sides of the bearings or supports from the wheel, each of said disks having two series of cutters, one rela- 130

tively stationary to cut a path for the disks, and the others movable toward and from the cutting wheel to cut a path for the bearings or supports thereof, substantially as set forth.

15. In a cutting apparatus for mining machines, the combination of the wheel provided with a series of peripheral cutters, a support for said wheel, a revolving disk, carrying a movable cutter, arranged on the opposite side of said support from the wheel, and a cam on said support adapted to move said cutter toward and from the wheel, substantially as set forth.

16. In a cutting apparatus for mining machines, the combination of the wheel provided with a series of cutters, a support for said wheel, a disk connected to the wheel and lying on the opposite side of the support therefrom, a relatively stationary cutter carried by said disk, a movable cutter carried by the disk, and means on the support for moving the last said cutter toward and from the cutting wheel, substantially as set forth.

17. In a mechanism for cutting coal or rock, the combination of a frame adapted to be made stationary against reactionary movement and adapted to be rotated horizontally around a vertical axis, a cutter carrying frame adjustable bodily vertically and adjustable bodily longitudinally on the stationary frame and adjustable horizontally with the stationary frame, and adapted to be rotated around an axis intersecting the vertical axis of the stationary frame, and a cutting apparatus supported on said cutter frame, said cutting apparatus having cutters which cut on lines crossing the lines of advance of the cutters and also cut on lines parallel to said path, substantially as set forth.

18. In a coal or rock cutting mechanism, the combination of a stationary frame, an advancing and receding cutting apparatus adapted to form a relatively elongated cut, a longitudinally movable frame on the stationary frame and supplemental to and supporting the cutting apparatus, and adapted to enter the kerf cut by the cutters and to be rotated around an axis on a line parallel to its path of advance, substantially as set forth.

19. In a mining machine, the combination of a bed frame or abutment frame adapted to be made stationary, a cutting apparatus which forms a relatively elongated kerf, a carriage supporting the cutting apparatus and movable therewith into the kerf and adapted to be adjusted while supported on the bed substantially as set forth, to hold the cutters as described to form said elongated cuts in either of several inclinations to the horizontal, and said carriage being universally adjustable around the lines of its

supporting connection with the bed, substantially as set forth.

20. In a mining machine, the combination of a bed or abutment frame, a set of cutters which form a relatively elongated kerf, a motor adjustable vertically and horizontally upon the bed, while the latter is stationary, and adjustable around a horizontal axis parallel to the path of advance of the cutting apparatus, power transmitting devices connecting the motor with the cutters, and a carriage frame supporting the cutters and motor and adapted to enter the kerf and movable forward and back with the cutters on the bed, substantially as set forth.

21. In a mining machine, the combination of a bed or abutment frame, a set of cutters adapted to form a relatively elongated kerf, a motor, power transmitting devices connecting the motor with the cutters, a carriage for the motors and cutters adapted to move into the kerf and to swing vertically and horizontally and also adapted to rotate around an axis which extends parallel to the path of advance of the carriage, and means for adjusting the carriage with the cutters and the motor bodily vertically on the bed, substantially as set forth.

22. In a mining machine, the combination of a bed or abutment frame, a set of cutters adapted to form a relatively elongated kerf, an endless chain for actuating the said cutters, a rotary wheel carrying the cutters, a carriage for the said cutters, chain and wheel, said chain being adjustable with the cutters around an axis in the plane of the chain, and means for bodily adjusting the chain and the cutters on the bed, substantially as set forth.

23. In a mining machine, the combination of a bed or abutment frame, a cutter wheel adapted to form a relatively elongated kerf, an endless chain for actuating said cutter wheel, a carriage for said chain and wheel adapted to enter the kerf and mounted upon and connected to the bed substantially as set forth to vibrate vertically and to vibrate horizontally and arranged to be adjusted relatively to the bed frame and to have the plane of the chain inclined to vertical planes and inclined to horizontal planes, substantially as set forth.

24. In a cutting apparatus for mining machines, the combination of the rotary cutter having its axis of rotation at an angle to its direction of advance, a bearing support for said cutter, an auxiliary cutter disposed adjacent the bearing support to rotate with and vibrate relatively to the plane of rotation of, the first named cutter, and means for so vibrating said auxiliary cutter, whereby a path is cut in advance of the bearing support, substantially as set forth.

25. In a cutting mechanism for mining machines, the combination of the bearing support, rotary cutters mounted on either

side of said support, an auxiliary cutter disposed adjacent the bearing support to rotate with and vibrate with respect to the planes of rotation of, the first-named cutters, and means for so vibrating said auxiliary cutter whereby a path is cut in advance of the bearing support, substantially as set forth.

In testimony whereof I affix my signature in presence of two witnesses.

DAVID N. OSYOR.
